UNITED STATES PATENT OFFICE.

FREDERICK W. HESSMER, OF JERSEY CITY, NEW JERSEY, ASSIGNOR TO AMERICAN MUSICAL SUPPLY COMPANY, OF JERSEY CITY, NEW JERSEY, A CORPORATION OF NEW JERSEY.

THREAD-CUTTING MACHINE.

Application filed October 6, 1919. Serial No. 328,761.

To all whom it may concern:

Be it known that I, FREDERICK W. HESSMER, a citizen of the United States, and resident of Jersey City, in the county of Hudson and State of New Jersey, have invented certain new and useful Improvements in Thread-Cutting Machines, of which the following is a specification.

My invention relates to improvements in thread cutting machines and the object of same is a machine adapted to cut relatively long and fine threads upon thin rods and a further object is to cut the thread as perfectly and accurately as possible at the same time making the operation as speedy as possible to reduce the cost of production considerably.

The nature of my invention will be fully understood from the description given below and from the accompanying drawings forming part of this specification.

In said drawings, Fig. 1 is a plan view of the machine, Fig. 2 is a side elevation, Fig. 3 a front elevation, and Fig. 4 shows certain details of construction explained in the course of the description.

Like numerals refer to like parts in the several figures.

1 denotes a bed plate of the supporting frame 2, the plate carrying a frame 3 upon which journals 4 and 5 are secured, shaft 6 being movably arranged in said journals. In about the middle of main shaft 6 there is a lead screw 7 provided adjoining pulley 8; the chuck 9 is provided at the free end of said shaft, the other end of same being movably engaged by one of the finger-shaped points of a powerful spring 10. This spring presses against the center point of shaft 6, whereas the other end of spring 10 is similarly held, in the same axis, in the upright arm 11. Upon frame 3 there is provided another journal 12 having a fork-shaped terminal between the arms of which a cylindrical block 13, having an upright arm 14 with a horizontal extension 15 which has as pivot the screws 16 and 17. The arm 15 has a hole 18 in which by screw 19 a stamp 20 with a thread, answering as to pitch and other measurements screw 7, is secured, the stamp 20 resting directly upon said thread. Arm 15 is furthermore at its free end ex-

tended into a hook 21 to hold a weight 22 thereby.

Upon frame 3 there is also mounted journal 23 to which at its upper end arm 24 is pivoted in such way that the downwardly bent end is movably secured to said journal by means of screw point 25 as a pivot, while rod 26, which at its other end is movably laid through journal 27, is rigidly secured to arm 24 by means of screw 25^a so that it will follow all movements of arm 24.

The free end of arm 24 has the shape of the letter V turned upside down, and is at its utmost end of a fork-like shape, between the arms of which a wheel 28 is movably arranged and held in position by means of pin 29. This latter wheel is resting (Fig. 3) upon the highest point of eccentric or cam-wheel 30 secured to auxiliary shaft 31 movably arranged in journals 32 and 33 and operated by pulley 34. At the other end of shaft 31 there is a guidewheel 35 secured to it, about one half of its face being broken away.

This guide wheel 35 presses against a little pulley 36 movably held by pin 37 within fork 38 of shaft 39 movably arranged within journals 40 and 41. Furthermore there is a standard 42 at the top of which by means of a screw a flat lever 43 is movably secured, said lever 43 having a slit 44 put over the upright pin 45 on shaft 39. At about its middle lever 43 is twisted 90 degrees and is provided with a hook 46 which is engaged by a powerful spring 47 held at its other end by hook 48 attached to bed plate 1. At the end of the vertical part of lever 43 same has another slit 49 (Fig. 3) through which a rod 50 is passed. This rod 50 is supported by a U-shaped frame 51 having in its upright arms 52 and 53 suitable openings through which the rod 50 is passing, being at the same time supported by same; the frame 51 in its turn is secured to the structure by being rigidly connected to the bent brace 54 held in position by strong screws upon journal 55 (Fig. 3) secured to bed plate 1. Between the upright arms 52 and 53 rod 50 is provided with two knobs 56 and 57 a certain distance from each other. It is obvious from the drawings that rod 50 leads to and disappears within the lowest

point of box 58 representing a magazine held in an inclined position by the plate 59, having a hole 59^a, secured to journal 55 which likewise carries oil tank 59^b by means 5 of support 60, the outlet 61 of tank 59^b discharging its contents to the lowest point of magazine or box 58; the arm 62 is secured to journal 55 and reaches into magazine 58 to regulate the feeding of the pins. 10 In the field of the bed plate between the length sides of frame 3, in which the journals 4 and 5 are put in, there is a block 63 (see Fig. 4) which is provided with a mold adapted to receive a cylindrical body. The 15 lowest point of the mold is on the same level with the lowest point of rod 50 as well as of the lowest point of the inside of box 58. In the arm 24 there is a slot in which a stamp 64, provided with a cutting die 65, secured 20 by screw 66 to said arm 24, screws 67 and 68 preventing said die 65 from slipping towards the sides; there is another recess or hole in said arm 24 close to wheel 28 in which, a strong iron rod 69 is movably secured therein to carry a heavy weight 25 at its lower end.

Close to pulley 8 there is on each side of same through the frame a hole 71 and 72, respectively, through which a belt may be 30 laid over pulley 8 and pulley 73 on shaft 74, same being actuated by loose and fast pulley 75 and 76, respectively; pulley 34 is actuated by means of pulley 77 indicated on shaft 74. A starter for shifting the belt 35 from loose to fast pulley and vice versa is not shown as it is not necessary to dwell upon such matters familiar to men who know the art, likewise lubricating devices are not particularly indicated when their 40 provision is a well understood matter.

I am going to describe now the operation of my new invention and before entering into any details of same I wish to state that the machine is constructed preferably for 45 cutting threads upon round iron pins which mostly have one of their ends flattened out so as to have a more or less prismatic point on this end, all the pins being of exactly the same length.

50 All the parts being well lubricated and the machine otherwise put in working shape the magazine 58 is filled with the pins, the prismatic heads showing towards block 63.

Assuming that the machine in the 55 moment it is started to run is standing exactly as seen in Fig. 1 it is obvious from the above that rod 50 during the continuation of the motion of guide wheel 35 will push the pin at the lowest point of box 58 out of same through the hole 59^a over to and unto the block 63.

The delivery of the pins is regulated by the arm 62 which reaches with its bent end into the magazine or box 58; as said 60 arm 62 terminates close to the bottom of

said box 58 in a distance only slightly larger than the diameter of a pin, it is obvious that only one pin at a time can pass to the lowest point of the box 58 to be acted upon by rod 50.

70 Chuck 9 has a recess of rectangular shape so that the prismatic end of the pins will fit in and as soon as rod 50 pushes the pin unto block 63 it is ultimately entering 75 chuck 9 and retained by it while being pressed against said chuck by rod 50. This is effected, as already alluded to above, by means of guidewheel 35. Part of the face of wheel 35 being broken away lever 43 is pushed outward when the high points of the 80 edge of guidewheel 35 press against wheel 36 thus pushing shaft 39 with its pin 45 outwardly which movement the lever is forced to follow. The reverse is taking 85 place when spring 47 contracts and presses lever 43 against pin 45 causing shaft 39 with wheel 36 to press against and follow the edge of guidewheel 35 all over the recessed part. The effect of these forth and 90 back motions is very important because any time lever 43 turns towards the magazine 95 58 it pushes rod 50 all through the lowest part of said magazine 58 thereby pushing the pin admitted by regulating arm 62 into the lowest part of said magazine, out of same and through hole 59^a unto block 63 where its prismatic head is caught and held by chuck 9. The pin immediately follows the rotation of shaft 6 and at this moment 100 arm 24 is also lowered until the stamp 64 with a die thread 65 at its lower end reaches down upon the pin resting during its rotation upon block 63. As the heavy weight 70 is acting upon arm 24 it is natural that the die thread 65 of stamp 64 will cut a 105 thread into the pin during its rotation. The length and other details of this thread are regulated by two factors, to wit, the lead screw 7 in connection with the die 20 sliding along said thread and the eccentric or edge cam 30 in connection with wheel 28 at the V bent end of arm 24. In Fig. 3 stamp 65 is seen lifted off block 63 as wheel 28 is practically at the highest point of said edge 110 cam 30 but from the form of this latter cam it is obvious that arm 24 will lower in the further course of rotation to alternately rise and lower according to the location of wheel 28 on cam 30; it is also self-evident from the form of this cam that die 115 thread 65 of stamp 64 will cut into the pin during the time shaft 31 needs to make approximately one half of a revolution and as the difference in diameter between pulleys 8 and 34 is very considerable, pulley 8, and shaft 6 are making in the meantime a considerable number of revolutions 120 so as to cut a thread of some length into the pins put unto block 63. It is obvious 125 that during this cutting action shaft 6 130

moves towards spring 10; because stamp 20 acts on lead screw 7, thereby causing the two finger-shaped ends of spring 10 almost to come together. In this moment the pin 5 has the desired length and the pin must therefore be removed to make room for the next one. The removal of the pin is caused by the effect of four different actions, two of same going on simultaneously.

10 The first of these four actions is the lifting of stamp 64 with the thread 65 off the pin by cam wheel 30, lifting arm 24, and the other simultaneous similar action is the lifting of arm 15, and thereby also of stamp 20, 15 off lead screw 7 by means of a projection 26^a indicated in dotted lines on shaft 26, said projection pressing arm 15 upwardly in the moment when arm 24 is lifted by cam-wheel 30. These two simultaneous actions allow 20 spring 10, of powerful construction, to push shaft 6 back to its original location after edge guidewheel 35 has shortly before pushed lever 43 to the outside thereby taking rod 50 along.

25 The withdrawal of rod 50 is so timed that there is no longer any pressure on the finished pin so as to allow the finished pin to be thrown out of chuck 9 and block 62 when spring 10 pushes shaft 6 back to its original 30 position. The finished pin drops into an inclined guideway 79 into a receiver (not shown) from where it is taken for further treatment. Oil is constantly dripping from tank 59^b into magazine 58 to lubricate the 35 pins before their transfer unto block 63.

Having now described my new invention I beg to state that some changes can be made without departing from the spirit of same and such changes come within the scope of 40 the appended claims.

What I claim is:

1. In a thread cutting device the combination of a support adapted to receive a cylindrical body or pin, a shaft, a chuck, having 45 a recess adapted to receive the pin, at one end of the shaft, means to deliver a pin unto the support and into the chuck, means to impart motion to the shaft, a die adapted to be pressed unto said pin, means to lower the 50 die while it is pressed unto the pin, means to shift the shaft away from the pin support while the die is pressed upon the pin, means to lift the die, and means to shift the shaft back to its original position.

55 2. In a thread cutting device the combination of a support adapted to receive a cylindrical body or pin, a magazine, having an inclined position for holding the pins, a shaft, a chuck, at one of its ends, said 60 chuck having a recess adapted to receive one of the pins, a rod adapted to make a reciprocating horizontal motion to enter the lowest point of aforesaid magazine and to deliver a pin therefrom unto the support and into the chuck means to impart motion to

the shaft, a die adapted to be pressed unto said pin, means to lower the dies while it is pressed into the pin, means to shift the shaft away from the pin support while the die is pressed upon the pin, means to lift the die 70 from the pin, and means to move the shaft back to its original position.

3. In a thread cutting device the combination of a support adapted to receive a cylindrical body or pin, a magazine, having an 75 inclined position, for holding the pins, a shaft, a chuck at one of its ends, said chuck having a recess adapted to receive a pin, a rod adapted to make a reciprocating horizontal motion to enter the lowest point of said magazine and to deliver therefrom a pin unto the support and into the chuck, means to impart motion to the shaft, a die secured to a pivotally arranged arm adapted to be lowered unto and lifted from the pin to be threaded, a lead screw upon the shaft, a die secured to a pivotally arranged arm resting upon said lead screw thereby moving the shaft away from the pin support, means to lift the aforesaid die from the lead screw, 80 and means to move the shaft back to its original position.

4. In a thread cutting device the combination of a support adapted to receive a cylindrical body or pin, a magazine, having an 85 inclined position, for holding the pins, a main shaft, a chuck at one of its ends, said chuck having a recess adapted to receive a pin, a rod adapted by means in connection with an auxiliary shaft to make a reciprocating horizontal motion to enter the lowest point of said magazine and to deliver therefrom a pin unto the support and into the chuck, means to impart motion to the shaft, a die secured to a pivotally arranged arm 90 pressed unto the pin by means of a weight and lifted therefrom by means of an eccentric cam secured to the aforesaid auxiliary shaft, a lead screw upon the main shaft, a die secured to a pivotally arranged arm resting upon said lead screw thereby moving the shaft away from the pin support, means to lift the aforesaid die from the lead screw, and means to move the shaft back to its 95 original position.

5. In a thread cutting device of the character as described, the combination of a shaft operatively connected with means to impart rotation, an auxiliary rotary shaft provided at its free end with an edge cam and an eccentric cam adjoining aforesaid edge cam, another auxiliary shaft operatively connected with aforesaid edge cam to make reciprocating horizontal motions, a bar pivoted secured to a standard and operatively connected with aforesaid auxiliary shaft making reciprocating motions, and of an arm, having a cutting die rigidly secured thereto, operatively connected with aforesaid eccentric cam.

6. In a thread cutting device of the character as described, the combination of the arm holding the cutting die, said arm being pivotally arranged at one of its ends upon 5 the supporting frame and being provided at its other end with a guide wheel sliding upon an eccentric cam causing the arm to move alternately in a down and upward direction, a rod rigidly secured to the arm in 10 the axis of its pivots and being journaled at its other end, said rod running parallel to the main shaft, an upwardly directed projection secured to said rod, another arm,

holding the die to fit the lead screw, pivotally secured at its end opposite to the pivot, of 15 the arm referred to above, a weight acting upon said arm at its end to hold it down upon the projection on the rod, this latter arm being lifted simultaneously with the arm holding the cutting die, thereby allowing the spring acting at the end of the main shaft to move it back to its original position. 20

Signed at Jersey City, in the county of Hudson and State of New Jersey this third day of October A. D. 1919.

FREDERICK W. HESSMER.
